T. H. DOAN, JR.
DRILLING MACHINE

Filed Nov. 27, 1925

INVENTOR:
THOMAS H. DOAN, JR.
by Alfred E. Baber,
His ATTORNEY.

UNITED STATES PATENT OFFICE.

THEODORE H. DOAN, JR., OF CLEVELAND HEIGHTS, OHIO, ASSIGNOR TO FOOTE-BURT COMPANY, A CORPORATION OF OHIO.

DRILLING MACHINE.

Application filed November 27, 1925. Serial No. 71,556.

The present invention relates to drilling machines, and is particularly well adapted for use in connection with what are termed usually high-duty or heavy-duty drilling machines, although it is not limited in use thereto.

In connection with high-duty drilling machines, it is important that the frame and work table be very rigid for if there is any spring action in either the frame or the table, then when the machine is subjected to heavy feeding pressure the drill will bind in the hole thereby greatly increasing the power required to drive the drill. This is especially true if the hole is a long one. Also, if the drill binds in the hole, the increased friction expands the drill thus causing it to bind still more tightly, which may result in the breaking of the drill.

One object of my invention is to provide an improved drilling machine wherein the frame and table are very rigid but wherein, at the same time, the drilling machine does not become unduly large and heavy.

Another object of my invention is to provide in a drilling machine an improved arrangement for taking care of the chips and the drilling compound or substance and conveying it away.

A further object of my invention is to provide an improved drilling machine which is comparatively narrow in width whereby when a number of machines are set side by side, the spindles will be brought comparatively close together. This is of importance because often one operative operates several machines and it is desirable that the spindles be as close together as possible in order that the operative may be required to walk the minimum distance in moving from one machine to another.

A still further object of my invention is to provide a drilling machine of a structure such that several or any desired number of machines may be bolted together to form a complete rigid installation which will occupy a minimum amount of floor space.

For what I believe to be novel and my invention, attention is directed to the following description and the claims appended thereto.

In the drawing, Fig. 1 is a perspective view of two drilling machines embodying my invention, the same being placed side by side and bolted together, and a portion of a wall of one of the machines being broken away to show the structure behind it; Fig. 2 is a sectional view in perspective of the base of one of the machines shown in Fig. 1; Fig. 3 is a sectional view of the base of one of the machines, and Fig. 4 is a top plan view of such base.

Referring to the drawing, 1 indicates a base which rests on a floor and comprises side walls 2, a front wall 3, a rear wall 4, a bottom wall 5 and a top wall 6. This forms what I term a cabinet or box. The walls of the cabinet are of suitable thickness and they are provided with webs or braces 7, the whole going to make up a structure which is strong and rigid. The top wall 6 slopes downward from the front to the rear as is best shown in Figs. 2 and 3. It is provided at the front and sides with flanges 8 and 9 which project above it, the flanges 9 extending to the rear end of the top wall. At the forward end of top wall 6 is an upward projection 10 which has a flat top surface 10a. This forms the table of the machine. The top surface of table 10 is about flush with the top edges of flanges 8 and 9. At the rear of table 10 is a second projection 11 having an inturned bolt-ing flange 12. This projection 11 I term the upright support.

Table 10 is spaced from flange 8 so that there is formed between them a transverse groove 13. The portion of top wall 6 which forms the bottom of groove 13 is shaped so that the bottom of groove 13 is highest at its center and slopes downward both ways. This is seen best in Fig. 1 where flange 8 is broken away on one of the machines. Table 10 and upright support 11 are spaced from side flanges 9 to provide side grooves 14 which at their forward ends merge into transverse groove 13. Table 10 and upright support 11 are spaced apart to provide a transverse groove 15 between them which at its ends opens into side grooves 14. The portion of top wall 6 which forms the bottom of groove 15 is shaped so that it is highest at the center 100

and slopes downward both ways as is seen best in Figs. 2 and 4. Thus it will be seen that table 10 is surrounded by grooves, all of which slope in directions to carry the cutting compound and chips to the rear of the machine.

Mounted on support 11 is an upright 16, the same being provided with an internal flange or other suitable means 17 which is bolted to flange 12. Bolted to the upper end of upright 16 is a head 18 which carries the drill spindle and other operating parts. This portion of the machine is illustrated only in outline as its specific structure forms no part of the present invention.

The cabinet or box which forms the base is rectangular and side walls 2 are straight and flat. At their forward and rear edges, side walls 2 project beyond front wall 3 and rear wall 4 to provide flanges 19 in which are slots or openings 20 adapted to receive bolts for fastening together two or more drilling machines. In Fig. 1, two machines are shown arranged side by side and fastened together with bolts 21.

The machine is operated in the usual manner, the piece to be worked upon being placed on table 10. The chips and cutting compound run into grooves 13, 14 and 15 and then down grooves 14 to the rear of the machine where they may be caught in a suitable receptacle or trough. The pitch of the grooves is made great enough so that the compound will carry the chips down them.

With this arrangement, it will be seen that I provide a means whereby the chips and compound are carried away to the rear of the machine in a most satisfactory manner, and that I accomplish this result without adding materially to the width of the machine.

By providing a rectangular base in the form of a cabinet or box, I provide a very stiff and rigid support for the table and for the upright and head of the machine. Thus I provide a drilling machine not likely to spring under heavy load. At the same time, I provide a structure which need not be made very heavy in order to give it the desired degree of rigidity.

Any desired number of machines may be placed side by side and be bolted together after the manner illustrated in Fig. 1. When this is done, a continuous rigid base structure is provided and the drill spindles are brought close together. There results also a rigid group of machines each having means for conveying the cutting compound and chips to its rear. When several machines are thus assembled side by side, I may provide with advantage a trough which extends along the back of the machines under the lower edge of top wall 6 to catch the chips and compound from all the machines and convey it away.

By providing an internal flange 12 on upright support 11, rather than an out-turned

flange, to which upright 16 is bolted, I am enabled to make a saving in the width of the machine, a thing which, as already pointed out, is of importance when several machines are to be located side by side.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. In a drilling machine, the combination of a base comprising side walls, a front wall, a rear wall and a downwardly and rearwardly sloping top wall, said side walls and front wall having extensions which project above the top surface of the top wall to provide a surrounding flange, a projection on the top wall which provides a table for the machine, an upright support on the top wall, said projection and upright support being spaced from said surrounding flange to provide grooves which slope toward the back of the machine for carrying away chips and cutting substance, and said side walls being flat whereby a plurality of machines may be arranged side by side and each deliver independently its chips and cutting substance to a common receptacle.

2. In a drilling machine, the combination of a base comprising side walls, a front wall, a rear wall and a downwardly and rearwardly sloping top wall, said side walls and front wall having extensions which project above the top surface of the top wall to provide a surrounding flange, a projection on the top wall which provides a table for the machine, and an upright support on the top wall, said projection and upright support being spaced from said surrounding flange and from each other to provide grooves for carrying away chips and cutting substance, the grooves between the projection and the upright and between the projection and the front wall extension sloping downwardly onto the rearwardly sloping top wall.

3. A unitary drilling machine structure adapted for use without change either by itself or in a battery of similar machines, said structure comprising a base having flat side walls, a front wall, a rear wall and a rearwardly and downwardly sloping top wall which overhangs the rear wall, said side walls projecting beyond the front wall at their front and rear edges to provide bolting flanges for use in fastening a plurality of machines together, and said side walls and front wall projecting above the top wall to provide a surrounding flange, a projection on the top wall which provides a table for the

machine and a second projection at the rear of the first named projection which provides a support for an upright, said projections being spaced from said surrounding flange to form grooves for carrying away chips and cutting substance, and said sloping top wall being adapted to deliver chips and cutting

substance to the rear of the machine and to a receptacle in common with other similar machines.

10

In witness whereof, I have hereunto set my hand this 21 day of November, 1925.

THEODORE H. DOAN, JR.
